[57] CLAIM

The ornamental design for a medical tubing connector, as shown and described.

DESCRIPTION

FIG. 1 is a perspective view of a medical tubing connector, showing my new design;

FIG. 2 is a side elevational view thereof, the opposite side being identical thereto;

FIG. 3 is a top plan view thereof, the bottom plan view being identical thereto;

FIG. 4 is a rear elevational view thereof;

FIG. 5 is a front elevational view thereof;

FIG. 6 is a perspective view of a second embodiment of FIG. 1;

FIG. 7 is a side elevational view thereof, the opposite side being identical thereto;

FIG. 8 is a top plan view thereof, the bottom plan view being identical thereof;

FIG. 9 is a rear elevational view thereof; and

FIG. 10 is a front elevational view thereof.

FIG. 6

FIG. 7

FIG. 8

FIG. 9

FIG. 10
